ENGINE

Alfred E. Walden, Detroit, Mich., assignor to
 Briggs Manufacturing Company, Detroit, Mich.,
 a corporation of Michigan

Application November 23, 1942, Serial No. 466,555

17 Claims. (Cl. 123—80)

This invention relates to internal combustion engines and especially to engines of the type in which the combustion chamber of each cylinder is principally or preferably to a large extent located within a rotatable valve in the cylinder head and driven from the engine crank or drive shaft in properly timed relation to the engine cycle.

An object of the present invention is to provide an engine of the foregoing type having improved means for mounting the rotatable valve within the cylinder head thereby reducing power losses by reducing friction, eliminating hot spots, and reducing leakage of gases consequent to operation of the engine.

A further object of the invention is to provide an internal combustion engine having a rotatable valve of the generally frusto-conical type provided with a portion of the combustion chamber and in which the wider end of the valve is positioned adjacent to and masked from the cylinder by a plate having a central orifice leading into the combustion chamber, the plate being annularly recessed to receive the end of the valve and the relation between these parts being such as to minimize gas leakage, overheating of the valve and frictional losses.

Still a further object of the invention is to provide an improved engine in which the frusto-conical valve has its inner end adjacent the cylinder largely confined within an annular recess in the mask plate and in such manner as to free the side wall of the valve along its bottom or inner edge, as well as freeing the bottom corner of the valve, from undesirable frictional engagement with the mask plate, the improved construction also permitting more efficient cooling of portions of the side walls of the valve near the bottom thereof which are subject to high bearing pressures.

Another object of the invention is to provide an improved internal combustion engine of the type having a generally frusto-conical valve containing a portion, and preferably most, of the combustion chamber, the bottom of the valve including the bottom outer corner of the valve being confined for rotation within a recessed portion of a mask plate interposed between the outer end of the cylinder and the valve.

A further object is to provide a structure as last above mentioned in which the bottom outer corner of the valve is freed from excessive frictional engagement with the mask plate.

Still a further object of the invention is to provide a mask plate having a three-sided an-

nular recess or channel to receive a correspondingly shaped portion of the bottom of the valve, the construction preferably being such as to permit more adequate cooling of the valve adjacent portions thereof subject to high bearing pressures, also reducing friction between the parts while rendering more devious the passage between the surfaces of the valve and mask plate tending to permit escape of gases and consequent loss of power.

Other objects of this invention will appear in the following description and appended claims, reference being had to the accompanying drawings forming a part of this specification wherein like reference characters designate corresponding parts in the several views.

Fig. 1 is a fragmentary sectional elevation illustrating a portion of a multi-cylinder engine embodying the present invention.

20 Fig. 2 is an enlarged fragmentary sectional elevation illustrating particularly the associated cylinder head and rotary valve structure shown in Fig. 1.

Fig. 3 is a transverse section taken substantially through lines 3—3 of Fig. 1 looking in the direction of the arrows.

Fig. 4 is an enlarged fragmentary sectional elevation illustrating a somewhat modified construction.

30 Fig. 5 is a view similar to Fig. 4 illustrating a further modification.

Before explaining in detail the present invention it is to be understood that the invention is not limited in its application to the details of construction and arrangement of parts illustrated in the accompanying drawings, since the invention is capable of other embodiments and of being practiced or carried out in various ways. Also it is to be understood that the phraseology or terminology employed herein is for the purpose of description and not of limitation.

In the drawings there are illustrated, by way of example, several embodiments of the invention as applied to an internal combustion engine of the spark ignition type designed particularly for the power plant of an aircraft. The invention may obviously be embodied in engines for other purposes, such as automotive, marine and industrial engines. For most uses the engine is of the multi-cylinder type, although any number of cylinder units may be employed in any given engine. In the present embodiment, for the purpose of simplicity, a single cylinder unit of the engine is illustrated, it being understood that the remaining cylinders of the engine are iden-

tical to the structure herein shown and described.

Referring to Fig. 1, the present engine comprises a suitable crankcase 20 within which is mounted a crankshaft 21 supported in bearings according to conventional practice. A cylinder 22 is secured rigidly to the crankcase and has its lower or inner end projecting thereinto. Mounted to reciprocate within the cylinder is a piston 23 adapted to be connected in the usual manner by a connecting rod 24 to the crankshaft 21.

In the present engine the combustion chamber of the cylinder is formed principally within a rotor or rotary member 25, this member comprising a frusto-conical body arranged immediately above the piston when at the top of its stroke and also having a cylindrical stem 26 projecting from the outer end of the rotor body. The rotor 25 fits within a correspondingly shaped substantially frusto-conical cavity 27 in an upper cylinder head member 28. The cylinder head of the engine may be said to comprise two portions or members secured together and to the upper end of the cylinder 22. In addition to the outer member 28 the cylinder head comprises an intermediate member 29 which may herein be termed the rotor mask or shield and forming the pressure control member for the rotor and head and also the throat opening from the cylinder into the combustion chamber.

The upper or outer end of the cylinder is formed with external threads which are engaged by internal threads on the cylindrical skirt portion of the head member 29 as indicated at 31. The member 29 in turn is provided with external threads which are engaged by internal threads on the cylindrical skirt portion of the outer cylinder head member 28, as indicated at 30. From this construction it will be seen that the cylinder head or mask member 29 may be screwed down tightly over the outer end of the cylinder 22 until the annular shoulder 29a of the member 29 substantially abuts against or engages the upper or outer edge of the cylinder, as shown in Figs. 1 and 2. Also it will be seen that the outer cylinder head member 28 is screwed down tightly over the member 29 until the bottom shoulder 28a of the head 28 substantially engages or abuts against the upper flat ledge or face of the mask member or plate 29.

The horizontal mask or shield plate 29 terminates centrally in a projecting annular flange 32 which forms the throat opening 33 into the combustion chamber 34 of the rotor member or rotary valve 25. The bottom or inner end of the valve 25 is provided with an annular right angled recess 25a to receive the throat flange 32 of the mask plate, there being a predetermined clearance 29b between the adjacent vertical faces of the portions 25a and 32 and also a similar clearance between the top face of the throat flange 32 and the adjacent portion of the valve 25, see Fig. 2. The valve 25 has an angular extension 25b extending into a correspondingly shaped recess in the mask plate, the bottom wall of the valve portion 25b being inclined or tapering downwardly and outwardly with respect to the mask plate. A predetermined clearance is provided between the bottom face of the valve portion 25b and the corresponding face 29c of the recess in the mask plate. The depth of the recess in this plate is such that the outer lower corner 25c of the valve is entirely housed within the recess. This corner portion 25c of the valve has

5 a rounded edge, and a predetermined clearance is provided between this valve portion and the wall 29d of the recess in the mask plate. The amount of the clearances between the bottom of the valve 25 and the adjacent portions of the mask plate at 29b, 29c and 29d will vary in accordance with varying conditions. In the present instance these clearances over and above what is customarily required for a running fit may be from five to ten thousandths of an inch.

10 The present engine is illustrated as being air cooled and, accordingly, the cylinder 22 is provided with projecting fins 35. Cooling fins 36 and 37 are also provided on the cylinder head members 28 and 29, respectively. It will be understood that the present engine is not limited to an air cooled engine as it will be apparent that any effective cooling system may be utilized.

15 The rotor 25 is driven through the medium of the stem 26 which is positively connected to a driving gear in such manner as to permit slight relative axial and radial movement between the driving gear and the rotor. The stem 26 of the rotor is provided with external longitudinal spines 38 and is also provided with internal threads within the cylindrical bore thereof. The rotor is driven by a gear 39 having suitable gear teeth 40, this gear being formed with a depending cylindrical hub or sleeve 41 having a clearance over the stem 26. The gear 41 also has internal tooth-like spines 42. A coupling member 43 fits within the annular space formed between the teeth 42 of the driving gear 39, this coupling member having exterior teeth or spines 44 fitting 20 into the spaces between the spines 42 of the driving gear and also having internal spines 45 fitting within the spaces formed by the spines 38 of the stem 26. The coupling member 43 has an annular tapered surface engageable with a correspondingly shaped tapered surface 39a of the gear 39. 46 is a clamping nut having external threads engageable with the threads of the valve stem 26 and having an outwardly projecting hex formed flange 47. Interposed between this flange and the end of the stem 26 is a spring washer 48 having a central aperture through which the clamping nut projects, the washer being of a sufficient diameter to engage the upper face of the gear 39, as shown in Fig. 2.

25 The rotor body 25 is cored entirely around the combustion chamber 34 to provide a cavity 49 which is closed at the upper end of the valve by means of a screw plug 50 screwed tightly into the threaded portion of the valve stem 26 below the clamping nut 46. Any suitable heat transfer or conducting medium, such as metallic sodium, is introduced into the cavity 49 through the hollow stem 26, and sealed therein by the screw plug 50.

30 Referring to Fig. 1, the gear 39, which is attached to the projecting stem of the rotor 25, is driven through the medium of a gear 51 attached to a top horizontal shaft 52. This shaft is of the desired length to permit simultaneous driving of the rotors of a plurality of cylinders arranged in line. Attached to the end of the shaft 52 is a gear 53 which is driven by a gear 54 secured to the upper end of a tower shaft 55. This shaft is suitably housed at 57 and has secured to the lower end thereof a gear 56 which is driven through the medium of a gear 58 attached to the crankshaft 21.

35 The rotor or valve 25 has a single port 59 in its side communicating with the combustion chamber 34 and adapted to register in succession with an intake port 60, a spark plug at loca-

tion 60, and an exhaust port 81. In this embodiment, therefore, the valve or rotor 25 is driven at one-half engine or crankshaft speed. As illustrated in Fig. 3, the upright side edges of the port 59 of the valve 25 are relieved or ground off at 59a. The amount of this relief will vary depending upon the metal employed in the construction of the valve and cylinder head. The relief may be several thousandths of an inch and its purpose is to permit expansion of the metal of the valve at points 59a without excessive binding against the wall of the cavity 27. During operation the edges of the valve opening 59 at 59a will expand sufficiently to bring these edges out into running engagement with the cavity 27 to provide a seal at the opposite edges of the valve port 59. This construction with the edges of the port relieved at 59a reduces wear at these points and, consequently, eliminates considerable friction.

Interposed between the upper end of the tapered wall of the valve or rotor 25 and the correspondingly tapered wall of the cylinder head cavity 27 is a rotatable thrust bearing ring 61 formed of a suitable material such as bronze or lead bronze alloy. The rotor is formed with an annularly extending recess to receive the frustoconical ring 61 which is a free floating bearing between the rotor and cylinder head. In like manner, there is interposed between the lower end of the tapered wall of the valve or rotor 25 and the tapered wall of the cylinder head cavity 27 a second rotatable thrust bearing ring 62 constructed similarly to the ring 61 and formed of the same metal alloy. This lower ring 62 is also housed within a similarly shaped annularly extending recess in the outer surface of the valve or rotor 25. It will be noted that the recesses in the rotor are somewhat wider than the bearing rings 61 and 62 so as to permit slight relative axial movement of the valve and rings during operation. The rotor 25 is relieved in the area 63 between the rings 61 and 62 thereby providing a clearance throughout the entire area between the bearing rings, which is normally somewhat greater than the clearance ordinarily provided for a running fit. This clearance at 63 in the present instance is about one to one and one-half thousandths of an inch and is preferably substantially equal to the combined running clearance at opposite faces of each of the bearing rings 61 and 62. In other words, the clearance at 63 is preferably twice the clearance at one face of each of the bearing rings 61 and 62. Hence, it will be seen that the surface 63 will be sealed as a result of the explosion pressure on the valve 25, thus avoiding any leakage of gas through the exhaust port 81 during the power stroke.

In the embodiment of Fig. 4, wherein the compression ratio is somewhat less than in the previous embodiment, the depth of the mask plate 64 is increased so as to provide a throat opening 65 of considerably greater depth than the throat opening 33. The valve 66, with the exception of its lower end, is constructed substantially the same as the valve 25, having a cavity 67 entirely surrounding the combustion chamber 34 and containing a suitable cooling medium such as metallic sodium. The lower or inner end of the valve 66 has an extension 66a extending within a correspondingly shaped annular recess in the mask plate 64. In this instance the side walls of the extension 66a are substantially parallel and the angle between each of these side walls

and the bottom face of the extension 66a is substantially a right angle. As in the previous embodiment the extension 66a of the valve is spaced from the adjacent walls 64a, 64b and 64c of the mask plate to provide a predetermined clearance which may be from five to ten thousandths of an inch as in the previous embodiment. It will be seen that the entire inner end of the valve 66 below the bearing ring 62 is housed within the annular recess in the mask plate 64. This corresponds to the construction in the embodiments of Figs. 1 and 2 in which the entire inner or lower end of the valve below the bearing 62 is housed within the recess in the mask plate.

In the embodiment of Fig. 5 the compression ratio of the engine is also less than in connection with the embodiment of Fig. 2, the depth of the mask plate being increased thereby providing a deeper throat opening 69. The valve in this embodiment is illustrated at 70 and is substantially the same in construction as the valve 25 with the exception of the shape of the lower end of the valve 70 which is housed within a recess in the mask plate 68. As illustrated in Fig. 5, the valve 70 has an extension 70a lying within a correspondingly shaped annular recess in the mask plate 68. In this instance the walls 68a and 68b of the mask plate recess extend substantially at a right angle to each other whereas the wall 68c of the recess is inclined upwardly and outwardly. The opposed faces of the valve extension 70a and the walls of the recess in the mask plate are spaced to provide a predetermined clearance which may be from five to ten thousandths of an inch as in the previous embodiments. Also, it will be seen that the entire extension 70a and the entire inner end of the valve 70 below the bearing ring 62 is housed within the annular recess in the mask plate. In this respect the construction in the embodiment of Fig. 5 corresponds to that in the previous two embodiments.

In the operation of the present engine the principal bearing loads during the explosion period are taken at the localities of the bearing rings 61 and 62. Consequently, it is important that sufficient cooling of these localities be provided. Furthermore, there is a considerable tendency of the valve to expand outwardly at its lower or inner end where the valve becomes quite hot. In each of the embodiments it will be seen that the cooling cavity extends well below the lower bearing ring 62. Thus, the cavity 49 in Fig. 2 extends at 49a below the ring 62 and opposite to the corner 25c. In Fig. 4 the cavity 67 extends at 67a below the bearing ring 62 and opposite the wall 64c. In Fig. 5 the cavity 71 extends at 71a below the bearing ring 62 and opposite the wall 68c.

Thus, in accordance with the present invention it is possible to reduce the temperature or better control the temperature of the bearing rings 62 since the entire area of the valve at the locality of this lower bearing ring is cooled by the cooling medium within the cavity 49, 67 or 71, the cooling medium being very close to these areas. Furthermore, by providing the clearances between the lower end of the valve and the adjacent walls of the recess in the mask plate and by extending the cooling cavity well down into this annular recess in the mask plate it is possible to reduce the temperature or better control the temperature of the lower or inner end of the valve. In particular there is less tendency of the corner 25c of the valve 25 or the lower outer corners of the valve extensions 66a and 70a in the embodiment

ments of Figs. 4 and 5 expanding outwardly to an excessive amount which would otherwise cause binding of the valve, frictional losses and excessive wear.

I claim:

1. In an internal combustion engine having a cylinder with a reciprocable piston therein, a cylinder head provided with a generally frustoconical cavity, a rotatable valve having a combustion chamber and a bearing on the wall of said cavity, and a mask plate interposed between the valve and piston and having a port communicating with said chamber, said valve having a portion extending within a recess in said mask plate beyond said bearing, there being a clearance between said portion and recess to permit expansion of said portion during operation of the engine.

2. In an internal combustion engine having a cylinder with a reciprocable piston therein, a cylinder head provided with a generally frustoconical cavity, a rotatable valve having a combustion chamber and a bearing on the wall of said cavity, and a mask plate interposed between the valve and piston and having a port communicating with said chamber, said valve having a portion enclosed at three sides within a recess in said mask plate.

3. In an internal combustion engine having a cylinder with a reciprocable piston therein, a cylinder head provided with a generally frustoconical cavity, a rotatable valve having a combustion chamber and a bearing on the wall of said cavity, and a cylinder head portion interposed between the valve and piston and having a port communicating with said chamber, said valve having a portion beyond said bearing confined at three sides in a recess in the outer face of said cylinder head portion.

4. In an internal combustion engine having a cylinder with a reciprocable piston therein, a cylinder head provided with a generally frustoconical cavity, a rotatable valve having a combustion chamber and a bearing on the wall of said cavity, and a cylinder head portion interposed between the valve and piston and having a port communicating with said chamber, said valve having the outer portion thereof at its inner end confined within a recess in said cylinder head portion and free to expand therein during operation of the engine to a greater extent than the adjacent side wall portion of the valve.

5. In an internal combustion engine having a cylinder with a reciprocable piston therein, a cylinder head provided with a generally frustoconical cavity, a rotatable valve having a combustion chamber and a bearing on the wall of said cavity, and a cylinder head member interposed between the valve and piston and having a port communicating with said chamber, said valve having the outer portion thereof at its inner end confined within a recess in said member, the clearance between said outer portion and member being greater than the clearance between the bearing and the wall of the cavity to permit relative expansion of said outer portion and bearing.

6. In an internal combustion engine having a cylinder with a reciprocable piston therein, a cylinder head provided with a generally frustoconical cavity, a rotatable valve having a combustion chamber and a bearing on the wall of said cavity, and a cylinder head portion interposed between the valve and piston and having a port communicating with said chamber, said

valve having a portion extending within a recess in said cylinder head portion beyond said bearing and also having a cooling chamber extending into said recess.

5. In an internal combustion engine having a cylinder with a reciprocable piston therein, a cylinder head provided with a generally frustoconical cavity, a rotatable valve having a combustion chamber and a bearing on the wall of said cavity, and a mask plate interposed between the valve and piston and having a port communicating with said chamber, said valve having the outer portion thereof at its inner end confined within a recess in said mask plate and also having a cooling chamber extending into said recess.

8. In an internal combustion engine having a cylinder and a cylinder head, a rotatable valve operable within a bearing cavity in said head and having a combustion chamber, and a cylinder head portion interposed between the outer end of the cylinder and the bottom of the valve and having a port providing communication between the cylinder and said chamber, said valve having the outer portion thereof at its inner end confined within a recess in said cylinder head portion.

9. In an internal combustion engine having a cylinder and a cylinder head, a rotatable valve operable within a bearing cavity in said head and having a combustion chamber, and a cylinder head portion interposed between the outer end of the cylinder and the bottom of the valve and having a port providing communication between the cylinder and said chamber, said valve having the outer portion thereof at its inner end confined within a recess in said cylinder head portion and also having a cooling chamber extending into said recess.

10. In an internal combustion engine having a cylinder and a cylinder head, a rotatable valve operable within a bearing cavity in said head and having a combustion chamber, and a mask plate interposed between the outer end of the cylinder and the bottom of the valve and having a port providing communication between the cylinder and said chamber, said valve having the outer portion thereof at its inner end confined within a recess in said mask plate beyond said cavity, the bottom wall of said cavity tapering away from said port.

11. In an internal combustion engine having a cylinder and a cylinder head, a rotatable valve operable within a bearing cavity in said head and having a combustion chamber, and a mask plate interposed between the outer end of the cylinder and the bottom of the valve and having a port providing communication between the cylinder and said chamber, said valve having the outer portion thereof at its inner end confined at three sides within a recess in said mask plate.

12. In an internal combustion engine having a cylinder and a cylinder head, a rotatable valve operable within a bearing cavity in said head and having a combustion chamber, and a mask plate interposed between the outer end of the cylinder and the bottom of the valve and having a port providing communication between the cylinder and said chamber, said valve having the outer portion thereof at its inner end confined at three sides within a recess in said mask plate, the outer of said sides tapering inwardly in the direction of said port.

13. In an internal combustion engine having a cylinder and a cylinder head, a rotatable valve operable within a bearing cavity in said head and having a combustion chamber, and a mask plate

interposed between the outer end of the cylinder and the bottom of the valve and having a port providing communication between the cylinder and said chamber, said valve and cylinder head cavity having cooperating tapered bearing surfaces and the valve being extended inwardly beyond said surfaces for cooperation with the mask plate.

14. In an internal combustion engine having a cylinder and a cylinder head, a rotatable valve operable within a bearing cavity in said head and having a combustion chamber, and a mask plate interposed between the outer end of the cylinder and the bottom of the valve and having a port providing communication between the cylinder and said chamber, said valve and cylinder head cavity having cooperating tapered bearing surfaces and the valve being extended inwardly beyond said surfaces into juxtaposition with angularly related surfaces of the mask plate.

15. In an internal combustion engine having a cylinder and a cylinder head, a rotatable valve operable within a bearing cavity in said head and having a combustion chamber, and a mask plate interposed between the outer end of the cylinder and the bottom of the valve and having a port providing communication between the cylinder and said chamber, said valve being extended inwardly beyond the bearing portion of said cavity into juxtaposition to surfaces of the 30

16. In an internal combustion engine having a cylinder and a cylinder head, a rotatable valve operable within a bearing cavity in said head and having a combustion chamber, and a member interposed between the outer end of the cylinder and the bottom of the valve and having a port providing communication between the cylinder and said chamber, said valve being extended inwardly beyond the bearing portion of said cavity.
- 5 17. In an internal combustion engine having a cylinder and a cylinder head, a rotatable valve operable within a bearing cavity in said head and having a combustion chamber, and a mask plate interposed between the outer end of the cylinder and the bottom of the valve and having a port providing communication between the cylinder and said chamber, said valve and cylinder head cavity having cooperating tapered bearing surfaces and the valve being extended inwardly beyond said surfaces for cooperation with the mask plate, and said valve having a cooling chamber extending inwardly beyond said surfaces.
- 10 18. In an internal combustion engine having a cylinder and a cylinder head, a rotatable valve operable within a bearing cavity in said head and having a combustion chamber, and a mask plate interposed between the outer end of the cylinder and the bottom of the valve and having a port providing communication between the cylinder and said chamber, said valve being extended inwardly beyond the bearing portion of said cavity.
- 15 19. In an internal combustion engine having a cylinder and a cylinder head, a rotatable valve operable within a bearing cavity in said head and having a combustion chamber, and a mask plate interposed between the outer end of the cylinder and the bottom of the valve and having a port providing communication between the cylinder and said chamber, said valve and cylinder head cavity having cooperating tapered bearing surfaces and the valve being extended inwardly beyond said surfaces for cooperation with the mask plate, and said valve having a cooling chamber extending inwardly beyond said surfaces.
- 20 21. In an internal combustion engine having a cylinder and a cylinder head, a rotatable valve operable within a bearing cavity in said head and having a combustion chamber, and a mask plate interposed between the outer end of the cylinder and the bottom of the valve and having a port providing communication between the cylinder and said chamber, said valve and cylinder head cavity having cooperating tapered bearing surfaces and the valve being extended inwardly beyond said surfaces for cooperation with the mask plate, and said valve having a cooling chamber extending inwardly beyond said surfaces.
- 25 22. In an internal combustion engine having a cylinder and a cylinder head, a rotatable valve operable within a bearing cavity in said head and having a combustion chamber, and a mask plate interposed between the outer end of the cylinder and the bottom of the valve and having a port providing communication between the cylinder and said chamber, said valve and cylinder head cavity having cooperating tapered bearing surfaces and the valve being extended inwardly beyond said surfaces for cooperation with the mask plate, and said valve having a cooling chamber extending inwardly beyond said surfaces.

ALFRED E. WALDEN.
